AUTOMATIC HOIST CONTROL

David Wertman, Mount Rainier, and Robert K. Bole, Bethesda, Md.

Application September 29, 1950, Serial No. 187,651

9 Claims. (Cl. 198—221)

(Granted under the act of March 3, 1883, as amended April 30, 1928; 370 O. G. 757)

1

This invention relates to hoists and more particularly to hoists of the bar type having means for automatically controlling the movement thereof in accordance with the condition of load thereon and the desired direction of movement of objects carried thereby.

Heretofore, equipment for raising or lowering articles from one station to another has usually been of the endless chain conveyor type, in which an endless chain passes through a hoist tube and over sprockets at the ends of the hoist, the chain being provided with uniformly spaced flights for carrying the articles being raised or lowered. The conveyor usually moves in stages to give the handlers opportunity to place objects on each flight as it reaches the loading station and to remove objects from each flight as it reaches the unloading station. A housing and hoist tube of a size to accommodate the chain, flights, and sprocket wheels require a large amount of space that could be otherwise used, as for the storage of the articles to be handled; particularly is this so when such hoists are used for serving ammunition to guns aboard fighting ships. Furthermore, in hoists of this class, the length of chain and the number of flights required must be at least double what is actually utilized for moving objects during a single cycle, and thus large masses which are not immediately concerned with object movement must be precisely controlled during operation of the hoist. Brakes or the like need be provided in the above-mentioned endless chain type hoist to retain it at the desired position between flight advancements, since the weight of all articles carried thereon tend to move the hoist downwardly. Hence, to properly control conveyors or hoists of this general class complicated hydro-mechanical mechanisms have heretofore been employed and, for completely automatic operation, the equipment required has been prodigious, subjecting the hoist to frequent breakdown and rendering the task of diagnosing casualties exceedingly complex.

The present invention contemplates providing a hydraulic conveyor or hoist of the bar type particularly adapted for vertical conveying of objects either up or down by stepwise increments through vertical reciprocation of the hoist bar. This bar is provided with a plurality of spaced pawls which engage objects to move them within a suitable hoist tube one flight for each bar reciprocation, the objects resting at each successive flight stage on tube pawls stationary with respect to bar reciprocation, so that the reciprocatory conveying movement of the bar need be only

2

slightly greater than the distance between two successive tube pawls, or the distance of one flight. A hydraulic control unit is provided having a plurality of valves whose operation is correlated with the load condition and hoist position, through suitable mechanical linkage therebetween, for automatically initiating object conveying movement of the hoist bar only when an operative load condition exists in the hoist tube and for automatically reversing and stopping the movement of the hoist bar at the proper points in its cycle. Means are provided for manually controlling the hoist in the event of valve breakdown or during drills.

15 An object, therefore, of the present invention is to provide an automatic control system for a hoist or conveyor functioning to initiate object conveying operations only when a certain load condition exists on said hoist.

20 Another object of the invention is to provide an automatic control system for a stepwise hoist or conveyor of the type indicated which is responsive to the hoist or conveyor load in initiating conveyor operation and thereafter being responsive to the movement of said hoist or conveyor in controlling the operation thereof.

25 Another object of the invention is to provide a reciprocating hoist or conveyor to move objects through a succession of steps or flights wherein the hoist or conveyor reciprocates over a distance substantially equal to the distance between two successive steps or flights.

30 Another object of the invention is to provide a hoist or conveyor which reciprocates between two positions for conveying objects by stepwise advancement in either of two directions as desired.

35 Another object of the invention is to provide a hoist or conveyor for moving objects between a loading and unloading station and a control system therefor responsive to the load condition existent on said hoist or conveyor, making the hoist or conveyor operative only when the loading station is charged and the unloading station is discharged.

40 Another object of the invention is to provide a conveyor and control system therefor, said control system determining the direction of conveyor load movement, said control system being responsive to the load condition on the conveyor to permit operation of the conveyor only under a desired load condition, and said control system being responsive to conveyor movement for controlling its operation.

45 Other objects and their attendant advantages will become apparent as the following detailed

description is read in conjunction with the accompanying drawing which is a semischematic view partly in section showing one embodiment of a bar hoist and a control system therefor embodying the present invention.

Referring now to the drawing, an electric motor 10 is shown which is preferably of a constant speed type and has an output shaft 11 to which is attached a hydraulic pump 12, preferably an axial piston type, whose direction and rate of discharge is controlled by such means as the tilting plate designated by the numeral 13. Motor 10 has a second output shaft 11a which drives through any suitable gear arrangement a servo pump 14 and a control pump 15, both of which are preferably of the positive displacement type. The function of these latter two pumps will be later described.

Hydraulic pump 12 is supplied with operating fluid, such as oil, from a suitable expansion tank 17 by conduit 16 which leads to certain ports or passages in a hydraulic piston control block 18. The purpose of the hydraulic pump 12 is to provide fluid pressure to the appropriate side of a double acting piston 19 which operates in a cylinder 28 to raise or lower a hoist bar, indicated generally by the numeral 20 which may operate in a conventional hoist tube (not shown). The hoist bar 20 is provided with pawls 21 which engage the objects, such as the projectiles 22, that are to be raised or lowered and move them between loading and unloading stations through a succession of flights or increments one flight at a time, the objects being retained at each flight by tube pawls 23. When the hoist bar has moved sufficiently to insure proper seating of the objects (hereinafter referred to as projectiles for purposes of illustration though it must be understood that the hoist is adaptable for raising or lowering other types of objects) on the proper tube pawls 23 its direction of movement is reversed so that on the next movement of the bar in the object advancing direction a projectile is moved one more flight by the hoist bar pawl 21 next above or below the one which last engaged the projectile according to whether the projectile is being raised or lowered.

In order, therefore, to reciprocate the rack bar 20, it is necessary to direct the fluid flow alternately to the opposite sides of the piston 19. The supply fluid enters the hydraulic piston control block 18 from conduit 16 through inlet passage 25 which is communicated through the check valves 25a and 25b with the pump 12. All passages, chambers, and the like communicating with passage 25 are completely filled with fluid, but it should be understood that with the parts of the hoist in the position shown this fluid is not under operating pressure. When the piston 19 is to be raised the tilting plate 13 is moved from the position illustrated, which is the neutral position, to the left toward the stop 24, either manually by means of a lever 13a or automatically by means to be later described. This movement of the tilting plate causes the pump to discharge oil through a lower passage 26 in block 18 to the chamber of an emergency stop valve 27 from which it flows via passageway and conduit 26a to the lower side of the piston 19. Fluid is also ported from conduit 26a through a lower check valve 26c to a lower buffering chamber 30, which is shown occupied by a buffering piston 31 on the bottom of the piston 19.

As the piston is driven upwardly by the pressure of the fluid acting on its bottom, the fluid

that is above the piston is forced back toward the pump through a conduit and passageway 32. Since the piston rod 19a occupies a certain portion of the space in the hydraulic cylinder 28, the fluid that is forced out of the cylinder does not supply the pump with a sufficient quantity to complete the upstroke of the piston 19. The excess fluid required is therefore supplied through the check valve 25a which admits the proper quantity from passage 25 to passage 32.

As the piston 19 approaches the top of the stroke, an upper buffering piston 33 on the top of the piston enters an upper buffering chamber 34 and decelerates the piston and hoist bar. Leakage between the piston 33 and the sides of the buffering chamber 34 permits the piston 19 to complete its stroke.

When the piston has reached the top of its stroke and before it has started to descend, pressure for a limited period is exerted on the bottom thereof by the continued pumping action of the pump 12. To prevent excessive pressure from building up a relief valve 35 is provided communicating passage 26 with passage 32 so that the unused fluid may readily recirculate through the pump 12 without damage to any of the parts.

After the projectiles 22 are in position to be seated on the tube pawls 23 as aforesaid and other operations to be described have been performed, the hoist bar 20 and piston 19 are ready to descend. To reverse the flow of fluid to the cylinder 28 the tilting plate 13 is moved from its left position toward the right stop 23. This may be done as before either manually by lever 13a or automatically, so that the pump 12 may now discharge oil through passage 32 to the top of the piston 19. Fluid also passes through an upper check valve 32a and enters the upper buffering chamber 34 in readiness for the next succeeding upstroke.

The fluid beneath the piston 19 is ported to the pump via passage 26a, the chamber of the emergency stop valve 27, and passage 26. As the piston approaches the bottom of the stroke, lower buffer piston 31 thereof enters the buffering chamber 30 and decelerates the piston as has already been described for the upstroke. Because of the space occupied by piston rod 19a, less fluid can be received above the piston 19 than is forced out from below. This excess fluid is discharged through a second relief valve 36 to a conduit 37 leading back to the expansion tank 17 as illustrated.

In the event that the hoist must be halted at any point in its operation, the emergency stop valve 27 is provided which is normally urged by a spring 40 toward the up or closed position. However, a solenoid 41a, which may be connected in one phase of the motor power supply, during normal operation holds the emergency valve 27 open. In order to stop the hoist a button (not shown) may be pushed to stop the motor 10 and permit the valve 27 to close quickly so that land 41 thereof can instantly shut off the flow of fluid through the passage 26. If the piston is on its upstroke the weight of the bar and the resistance of the fluid above the piston will decelerate and stop these members almost instantaneously. Should the piston, however, be on the down stroke excessive pressure is likely to occur. To avoid this upper land 42 of valve 27 uncovers a passageway 43 so that passage 26a will be in communication with return conduit 37 through a relief valve 43a, which is set to open only when

a maximum pressure obtains beneath the piston 19.

As has been hereinbefore mentioned, motor 10 drives a control pump 15 and a servo pump 14 which receive fluid from tank 17 through a branch line 16a. This fluid is pumped through suitable filters 15a and 14a, and lines 15b and 14b respectively to certain ports and passages in a control valve block, indicated generally by the numeral 50. The pumps 15 and 14 may have substantially similar characteristics and it is to be understood that they create a constant positive head in the lines 15b and 14b at all times during the operation of the hoist.

From lines 15b and 14b fluid flows to chambers of a function control valve 51 whence it passes into passageways in the control valve block 50. The function control valve is operated by a hand lever 52 which is illustrated in the "raise" position. When the lever 52 is moved to the "lower" position the function control valve 51 covers and uncovers other ports and passageways so that the hoist operates to lower the projectiles.

Referring now to the right-hand portion of the drawing and particularly to the system of linkages there illustrated, there will be observed a lower bell crank 53 which has a fixed pivot 54. The end of the short arm 53a of the bell crank is arcuate as shown and the long arm 53b is urged in a counterclockwise direction by means of a spring loaded rod 56 which operates through an aperture in a fixed portion 56a. The arrangement is such that when a projectile is placed on the loading platform 57 of the hoist tube, the side of the projectile pushes against the arcuate portion of the arm 53a to pivot the bell crank 53 clockwise and force the rod 56 downwardly against its spring. Pivotally attached to the end of the arm 53b is an elongated link 58 which is pivotally secured at its upper end to one end of a couple link 59 which in turn is pivotally attached at its center to one arm of a small bell crank 59 having a fixed pivot 59a. Attached to the opposite end of couple link 59 is the lower end of a link 60 which is pivotally secured at its upper end to an elongated arm 61a of an upper bell crank 61 which is pivoted at 64 and urged clockwise by the spring loaded rod 62 operating through a fixed portion 62a. The arrangement is such that when a projectile contacts the arcuate end of the short arm 61b, the bell crank 61 will be rotated counterclockwise against the rod 62 forcing it upwardly against the pressure of its spring.

To the upper arm of the aforesaid small bell crank 59 there is pivotally secured one end of an elongated horizontal rod 65 whose opposite end extends through the wall of housing member 50a and is pivotally secured to a pivot arm 66 which is mounted on a suitable bracket 66a attached to the side of the control valve block 50. The length of arm 66 is substantially equal to the length of the upper arm of the bell crank 59 so that movement of the latter will impart motion through link 65 and arm 66 to a valve stem 67a of a valve 67 disposed in the top of the control valve block 50. It should be noted that valve 67 is provided at its left end with a spring 67b which normally acts between shoulders to move and to retain said valve in the position illustrated, which is the neutral position.

The valve 67 is an interlock valve, the operation of which will become readily apparent as the description proceeds, and its function is to initiate the conveying operations according to the load

condition. For example, with the two projectiles 22 seated on the tube pawls 23 at the two intermediate flights as illustrated in the drawing, when a projectile is put on the loading platform 57 the lower bell crank 53 is rotated clockwise causing couple link 58 to rotate counterclockwise about the end of link 60 which is restrained from upward movement by the spring loaded rod 62. Hence couple link 58 acts as a lever with the lower arm of small bell crank 59 pivoted midway of its length. It will be apparent, therefore, that bell crank 59 will pivot clockwise and thus draw valve 67 toward the right position, shown in dotted lines, to initiate a hoisting operation.

When the lowest projectile has cleared the arm 53a of lower bell crank 53, all the parts of the linkage arrangement will be returned through the action of the spring loaded rod 56 and interlock valve spring 67b to the positions shown in the drawings. However, as the hoist continues to ascend, the uppermost projectile engages the arm 61b of the upper interlock bell crank 61 and cams it in a counterclockwise direction so that now the couple link 58 will pivot as a lever counterclockwise about the end of link 60. This causes small bell crank 59 to rotate counterclockwise so that the valve 67 moves to the left to the position also shown in dotted lines. This same effect is achieved when a projectile is placed in the top of the hoist tube during lowering operation and, as will become apparent, in the latter instance a lowering cycle is initiated. When the upper projectile is moved out of contact with the upper bell crank 61, the interlock valve and the above-described linkage system assume the position shown in the drawing and no further projectile moving operations may be performed until the interlock valve 67 is moved one way or the other by a projectile acting on either the upper or lower interlock bell crank 61 and 53 in a manner substantially as described.

When projectiles are in the top and bottom positions of the hoist tube at the same time, the forces acting on couple link 58 merely rotate it about its pivot so that small bell crank 59 is not influenced to move valve 67 in either direction, and the bar 20 is not actuated. Thus a projectile cannot be raised against the base of one in the uppermost position before it has been removed from the hoist tube; nor can a projectile be lowered on the nose of one seated on lower platform 57. If desired the interlock valve may also be operated in a similar manner and in combination with the shown linkage by the conventional shutters (not shown) which are normally provided at the top and bottom of a projectile hoist. Thus, when either shutter is open the arrangement of linkages connected therewith may operate to place the interlock valve in such a position that operation of the hoist cannot be resumed until the shutters have been properly closed.

Referring now to the valve control block 59 and particularly to servo inlet passage 14b, with the function control valve 51 in the "raise" position fluid passes from a chamber thereof through two vertically spaced passageways 70a and 70b. The passage 70b admits fluid to the interlock valve 67 where further passage is blocked by a land thereof. Passage 70a admits fluid to a chamber of a reversing valve 73 from which fluid flows via a passage 70c through a chamber in a bottom-of-stroke valve 72, to be later described, to a conduit 75 70d leading to the right-hand end of a piston 82

which operates in a control block 80 and has pivoted medianly thereto the upper end of the tilting plate 13. Fluid is also ported from conduit 70d through an orifice 83a to a chamber of a right neutral positioning piston 83 having an extension 83b which extends horizontally through a suitable aperture in the tilting plate control block 80 to abut the right end of tilting plate positioning piston 82 when the parts of the hoist are in the position shown.

Located above the reversing valve 73 and branching to the left and right from the passage 70a is a horizontal passage 70f from the right branch of which at 70c' fluid flows through a chamber of the reversing valve 73 and a passage 70k to a chamber in the bottom-of-stroke valve 72 and passes to a conduit 70g leading to the left-hand end of the tilting plate positioning piston 82. Fluid is also ported from conduit 70g through an orifice 84a to a chamber of a left neutral positioning piston 84 which is provided with an extension 84b and is similar in all respects to the piston 83 already described.

It will now be apparent that with all of the parts of the hoist in the position illustrated fluid flows equally to both sides of the tilting plate positioning piston 82 and the tilting plate will be thus retained in its neutral position so that no fluid may be discharged by pump 12 to either side of piston 19. Since servo fluid cannot otherwise escape from the system a relief valve 85 is provided in the left end of the horizontal passage 70f to vent excess fluid to a drain passage 17a leading back to the expansion tank 17.

With the function control valve 51 in the position of "raise" and with no projectile in the top flight of the hoist so that upper interlock bell crank 61 is not retracted, when a projectile is placed on the loading platform 57 the lower interlock bell crank 53 will be rotated to move the interlock valve 67 to its right position as already described. This ports the aforesaid passage 70b to a chamber 67c of the interlock valve which communicates the former with a passage 71 so that fluid may flow downwardly through the control block 50 to the right-hand chamber of the bottom-of-stroke valve 72 whence it passes upwardly through a passage 71a to the right-hand end of the reversing valve 73. This end of the reversing valve is provided with horizontally spaced annular grooves with which nonpositive detents 73c engage so that the reversing valve 73 may be releasably retained in the right position shown or in the left position to which it will be forced by the admission of the fluid to its right end. When the reversing valve 73 has been moved to the left the passages 70c and 70k will be closed to communication with passages 70a and 70f. However, a passage 70h will be uncovered by the reversing valve 73 and servo fluid continues to flow through passage 70a to conduit 70d and the right hand end of the tilting plate positioning piston 82. Conduit 70g, leading to the left end of the tilting plate positioning piston, is now communicated by way of a passage 70' with a return passage 90 in communication with drain passage 17a leading to the expansion tank 17.

Since pressure is now exerted only on the right end of the tilting plate positioning piston and the left hand end of this member is vented to the expansion tank, the tilting plate positioning piston 82 is moved to the left causing the tilting plate 13 to approach the stop 24. The orifice 84a limits the speed of fluid escape from the chamber of the left neutral positioning piston 84 there-

by controlling the acceleration of the hoist bar 20 to within desired limits. Orifices 83a for the right neutral positioning piston 83 serves in a similar manner to control the rate of acceleration of the hoist bar when starting its down stroke.

Referring now to hoist bar 20 and particularly to the pawls 21 thereon it will be observed that they are pivotally mounted in slotted members 21a and are of the shape shown so that when the hoist descends during the down stroke of a raising cycle the pawls may be pushed aside by vertical sides of projectile on lower flights so that the downward movement of the bar will not be obstructed. When the bar has descended sufficiently so that each pawl is beneath the projectile it is to engage on the next ascent, gravity or light springs (not shown) rotate the pawls clockwise to projectile engaging position, suitable stops (not shown), of course, being provided to retain the pawls in this position.

On the lower two slotted members 21a are projecting bosses 21b and 21c. The purpose of these bosses is to engage a lever arm 91 which is pivotally supported by bracket 91a secured to the side 25 of the control valve block 50. Attached to the shaft and operated by the lever 91 in fixed angular relationship therewith are two arms 92 and 93. The arrangement is such that when piston 19 approaches the bottom of its stroke, the upper boss 21b on the hoist bar engages lever 91, causing the end of arm 92 to contact the horizontally projecting stem of the bottom-of-stroke valve 72 and force it to the left against the pressure of a spring 72b. In a like manner, when the piston 30 19 approaches the top of its stroke, the lower boss 21c engages lever 91 moving it counterclockwise so that end of upper arm 93 contacts the horizontally projecting stem of a top-of-stroke valve 80, and urges it to the left against the pressure of a spring 80b. It will be noted that intermediately disposed on the arm 93 is a rod 93a whose function is to contact the projecting stem of a tube pawl control valve 95 to be hereinafter described. Valve 95 is movable between the position shown 35 and a right extended position indicated by the dotted lines. With valve 95 in the position shown, a spring about rod 93a allows a certain amount of lost motion thereof to permit lever 93 to continue moving after valve 95 has been contacted by rod 93a so that valve 80 may be thereafter shifted to the left as above-described.

Immediately, therefore, after a projectile has been placed on the lower platform 57 of the hoist tube and the reversing valve 73 has been moved to the left so that fluid is delivered by pump 12 to the underside of piston 19, all as above-described, the boss 21b on the hoist bar 20 releases lever 91 so that spring 72b of bottom-of-stroke valve 72 may move it to the right to block the fluid flowing through passage 71a to the right end of the reversing valve 73 which nevertheless, remains in its left position because of the aforesaid non-positive detents 73c. With the bottom-of-stroke valve 72 in its right position, passage 71a is vented to the expansion tank 17 through a horizontal passage 17c communicating with drain passage 17a. As piston 19 ascends, the projectiles 22 on the tube pawls 23 are engaged by the hoist pawls 21 to be lifted one flight as described. When the lowest projectile moves out of contact with bell crank 53 the interlock valve 67 moves to the neutral position shown so that fluid no longer flows in the passage 71 to the bottom-of-stroke valve 72. As the piston 19 approaches the top of its 75 stroke and has lifted each projectile above its

corresponding tube pawl the top-of-stroke valve 80 is forced by end of arm 93 to the left against the pressure of its spring 80b. A horizontal extension 80c secured to the left end of the top-of-stroke valve 80 abuts the right end of a valve 100, hereinafter referred to as a latch valve, and also moves it to the left against the pressure of its spring 100a. The function of the latch valve will be later described.

With the top-of-stroke valve 80 in the left position, a horizontal passageway 70p, branching from passage 70a, is communicated with a passage 70r which admits fluid to the left end of the reversing valve 73 forcing it to the right to the position illustrated where it is retained by the nonpositive detent 73c. It must be remembered that bottom-of-stroke valve 72 has already been moved to its right hand position by its spring 72b. Hence, when the reversing valve 73 is moved to the right, passageway 70d will be communicated through a chamber in the bottom-of-stroke valve 72 and a passage 70i with a chamber of the reversing valve 73 from which fluid may flow through aforesaid passage 90 to return passage 17a and thus be discharged to the expansion tank 17. Furthermore, when the bottom-of-stroke valve 72 is in its right most position servo fluid at the extreme right end of the horizontal passage 70f is now communicated through the reversing valve 73, a passage 70m, and a chamber of the bottom-of-stroke valve, with conduit 70g leading to the left end of the tilting plate positioning piston 82 to urge the plate toward the right stop 23. This reverses the hydraulic pump 12 as explained so that the piston 19 starts its descent. After about the first inch of downward movement of the hoist, lower boss 21c thereon releases lever 91 so that top-of-stroke valve 80 and latch valve 100 are returned to their right hand positions by their springs 80b and 100a respectively thereby blocking fluid flow from passage 70p to the left end of the reversing valve. Passage 70r which had received fluid from passage 70p is now vented through the chamber of the top-of-stroke valve to return passage 17a so that fluid on the left end of the reversing valve can be returned to the expansion tank when that valve is next moved to its left position. As the hoist bar descends and before it has reached its maximum velocity the projectiles are deposited on their corresponding tube pawls so that the hoist completes the remainder of its down stroke in an unloaded condition.

As the hoist nears the bottom of its stroke the bottom-of-stroke valve 72 is forced to the left so that all of the valves of the hoist assume the position depicted in the illustration and fluid thus flows equally to both sides of the tilting plate positioning piston 82. Since the right hand end of the tilting plate positioning piston is in abutment with the extension 83b of the right neutral positioning piston 83, a differential area is provided by the latter against which the fluid may act to move piston 83 and piston 82 to the left until the left end of the latter contacts extension 84b of the left neutral positioning piston 84. The forces acting on both sides of a tilting plate positioning piston 82 will now be balanced so that this member will be retained in the neutral position of the drawing resulting in a cessation of pumping action by the pump 12.

It should be understood that the hoist as described to this point, has been primarily depicted as it would be employed to raise projectiles. When it is desired to lower projectiles, it will be

obvious that the hoist 20 must first ascend toward its uppermost position before the hoist pawls 21 engage any projectiles in the hoist tube. In order to accomplish this, therefore, means must be provided to move the hoist pawls 21 clear of projectiles immediately above these pawls as the hoist ascends and furthermore, means must be provided to retract the tube pawls 23 clear of descending projectiles until each has been moved to the next lower flight at which point the tube pawls must assume a projectile retaining position. The tube pawls must remain in this position until on the next upstroke the proper hoist pawls have lifted the projectiles from their corresponding tube pawls whereupon they must again be retracted clear of all projectiles so that the latter may be lowered an additional flight.

With reference to the right side of the drawing the means for actuating the tube pawls in correlation with hoist bar position comprises a bar 107 mounted atop a double acting piston 103 disposed in a cylinder 104 which receives fluid in proper sequence to its top or bottom by means of upper and lower conduits 105 and 106 respectively. The bar 107 has equally spaced thereon suitable slotted portions 23c in which are pivotally secured the ends of link arms 23a whose opposite ends are pivoted to fixed portions 23b of the hoist tube. The tube pawls 23 are also pivoted to the fixed portions 23b and are so arranged that they may be moved clockwise relative to link arm 23a by ascending projectiles during the upstroke phase of a raising cycle. However, when the loaded hoist bar is on the down stroke phase of a lowering cycle the tube pawls 23 are retracted in a clockwise direction by the link arms when they are moved downwardly by the admission of fluid to the top of cylinder 104 in proper timed relationship with hoist bar position.

Referring to the hoist bar 20 the pawls 21 thereof are provided with toes 21d which project slightly to the left of the slotted members 21a as illustrated. An elongated vertical rod 108, mounted atop a double acting piston 109 operating in a cylinder 110, has thereon pairs of spaced collars 108b, the lower collar of each pair being fixed to the rod 108 and the upper collar being slidable thereon and spring urged downwardly as illustrated. Between the adjacent faces of each pair of collars there are disposed the rounded bifurcated ends of arms of tripping cams 108c which are pivoted to fixed portions 56c. The tripping cams extend into the path of the toes 21d of the bar pawls 21 when the piston 109 is moved downwardly by the admission of fluid to the upper end of the cylinder 110. The tripping cams are extended throughout the entire lowering cycle and are contacted by the toes 21d on both the up and down stroke of the hoist bar. On the upstroke, the hoist pawls engage the tripping cams 108c and are rotated counterclockwise clear of projectiles immediately above them. When the hoist bar pawls 21 have passed above the projectiles thus avoided they return to their normal position. The toes on the pawls 21 are arranged so that they do not engage the tripping cams at the top of the stroke. On the down stroke of the loaded hoist bar, the toes 21d again contact the tripping cams 108c which are rotated clockwise against the springs of the upper slidable collars on the rod 108 and thus do not obstruct the hoist bar.

The tripping cam operating piston 109 and the tube pawl control piston 104 are actuated by control fluid delivered by the control pump 15. With the lever 52 in the position of "raise," control

fluid from conduit 15b enters the control valve block 50 to the appropriate chamber of the function control valve 51 whence it is ported to conduit 120 leading to the bottom of the cylinder 110 urging piston 109 in the upper position shown where it remains throughout all phases of projectile raising cycles. A branch passage 120a depending from conduit 120 admits fluid to the bottom of a piston 115 operating in the tilting plate control block 80 as illustrated. Piston 115, which will be hereinafter referred to as a stroke limit piston and later described in detail, is also retained in the up position throughout projectile raising operations. Additional control fluid is ported from the function control valve 51 to a 15 passageway 122 which conducts fluid to the right hand end of a tube pawl control valve 95 so that this member will be urged to its left position throughout the projectile raising cycle. With the tube pawl control valve 95 in this position fluid is now communicated through the left chamber thereof with the conduit 106 leading to the lower end of the tube pawl control cylinder 104 urging piston 109 upwardly where it also is retained throughout the entire projectile raising cycle.

Fluid not required for retaining these three pistons in their upper position escapes through an orifice 120b, located near the upper left hand corner of the control block 50, to the drain passage 17a and returns there through to the expansion tank 17. Orifice 120b further serves to maintain a back pressure in the control circuit to insure retention of all pistons in their upper position. The tube pawl control rod 107, the hoist pawl control rod 108, and the stroke limit piston 115 are provided with springs 107a, 108d, and 115a respectively which also urge each of the aforesaid members to their upper position shown in the drawing.

When lever 52 is moved downwardly to "lower" position the tripping cam operating cylinder 110 and the stroke limit piston 115 are moved immediately to their down position where they remain throughout projectile lowering cycle. This occurs when the function control valve uncovers a conduit 121 which admits fluid to the upper end of tripping cam control cylinder 110 and to a branch passage 121a leading to the upper end of the stroke limit piston 115. Furthermore, with the function control valve in the "lower" position, a chamber thereof communicates conduit 120 with the drain passage 17a so that as the pistons 109 and 115 are moved downwardly the fluid therebeneath will be returned to the expansion tank 17. Additional control fluid is conducted through a chamber of the function control valve to a passage 125 leading to a chamber of a differential piston 95a on the left end of the tube pawl control valve 95. Fluid which had previously been acting on the right-hand end of tube pawl control valve 95 as above explained is vented to the expansion tank through passage 122 which is now communicated with drain passage 17a through the function control valve.

Control fluid acting on the differential piston 95a moves the tube pawl control valve 95 to its extreme right position to communicate passage 125 with passage 106 leading to the bottom of the tube pawl control piston 103 so that it continues to remain in the upper position. As the hoist bar 20 moves upwardly and approaches the top of its stroke, rod 93a on the upper hoist-operated arm 93 contacts the rightwardly extending stem of the tube pawl control valve 95 and forces

it to the left against the pressure of control fluid acting on the piston 95a. The spring force on rod 93a is greater than the hydraulic force on piston 95a so that the lost motion of rod 93a does not come into play until valve 95 has been moved completely to the left. The central small land of valve 95 shuts off control fluid from passage 125 to conduit 106 leading to the bottom of tube pawl control cylinder 104 and the latter passage is vented to passage 122 which, it will be remembered, is in communication with the expansion tank 17. At the same time passage 125 is communicated through the right chamber of the tube pawl control valve with a passage 126 leading to the latch valve 100 which is still in the right extended position of the illustration so that further passage of the fluid is temporarily blocked. As the hoist bar 20 continues its ascent and after all projectiles have been lifted from their tube pawls, the end of arm 93 contacts the stem of top-of-stroke valve 80 and moves it and the latch valve 100 to the left against the pressure of their springs 80b and 100a respectively. When the latch valve 100 has been thus moved, control fluid is communicated through the central chamber thereof with conduit 105 leading to the top of tube pawl control cylinder 104. The projectiles having already been lifted from the tube pawls 23, they are now retracted by the downward movement of piston 103 in the manner previously indicated. It will be noted that from conduit 105 fluid is admitted to a chamber 100b at the right-hand end of the latch valve 100 so that it will be retained in its left position in order that fluid will continue to act on the top of piston 103 for a certain period of time after the loaded hoist bar starts its descent and the top-of-stroke valve 80 has been released by the arm 93 to return to its right extended position.

As the loaded hoist bar 20 moves downwardly, rod 93a on arm 93 releases the tube pawl control valve 95 after the bottom of each projectile has passed below the tube pawl from which it was lifted. Pressure acting on the piston 95a of the tube pawl control valve 95 again shifts it to its extreme right position whereby fluid flowing from passage 125 is no longer communicated with passage 126 and the latter is vented to the expansion tank through passages 122a, 122, and the function control valve. This permits the spring 100a to move the latch valve 100 to the right, porting passage 105 to the passage 90 communicating with the drain passage 17a so that fluid above the piston 103 will be vented to the expansion tank. Passage 125 is now communicated with conduit 106 to again admit fluid to the bottom of piston 103 to move it to its upper position to thereby extend the tube pawls 23 to projectile retaining position in readiness to receive the projectiles as the hoist bar continues its descent.

It will be noted that with the function control valve 51 in the position of "lower" no escape is provided for excess fluid in the control circuit except through a relief valve 120c which is provided in the left-hand side of the control block 50. This relief valve is set to maintain in the control circuit substantially higher pressure than that provided by the aforesaid orifice 120b, which is now no longer in the control circuit, so that all pistons operated by the control fluid during a lowering cycle will be positively moved and held against the forces of the springs, or against all

other forces imposed on these pistons during the process of lowering projectiles.

The stroke limit piston 115 operating in the tilting plate control block 80 is provided with a depending extension 115b which is adapted to engage a groove or slot 82b on the top of the tilting plate positioning piston 82 when stroke limit piston 115 is in its down position during the lowering cycle. The slot 82b is of a size to permit the tilting plate positioning piston 82 to be moved to its leftmost position to allow pump 12 to deliver full fluid flow to the lower end of the hydraulic cylinder 28 as hereinbefore described. The left end of the slot 82b, however, abuts the extension 115b of the piston 115 when the piston 82 is urged to the right during the down stroke phase of a lowering cycle so that the tilting plate 13 may not be moved to its full right position. Thus, the loaded hoist bar moves down by the force of gravity rather than by hydraulic pressure and consequently, under this condition, pump 12 actually becomes a motor, and the electric motor 10 acts as a generator, to prevent the hoist bar from moving down at a speed greater than that for which the tilting plate positioning piston 82 is set.

Referring to servo outlet passage 14b, it will be noted that when the function control valve is in its down position servo fluid is no longer in communication with passage 10b leading to the interlock valve 67. Servo fluid is, however, ported to an upper passage 10s leading to the interlock valve which passage is uncovered when a projectile acts on the upper interlock bell crank 61, as previously described, to move the interlock valve 67 to the left. This initiates the up-stroke phase of a lowering cycle in a manner similar to the placing of projectile on the loading platform 57 to initiate the upstroke phase of a raising cycle.

It should be noted that the servo circuit is completely separate from the control circuit, the only common passageways being the drain passage conducting fluid to the expansion tank 17. Furthermore, it should be noted that all valves that do not ordinarily receive fluid on their ends during the operation of the hoist, may be provided as shown, with suitable end chambers 17b to receive any fluid that may leak around the lands of the valves. Suitable passageways communicate these end chambers with the main drain passages so that such leakage may return to the expansion tank. It should be noted further that housing 50a is fluid tight and is normally completely filled with fluid to provide a seal about the valves operating in the control block 50.

The operation of the hoist is as follows:

With no projectiles in the hoist tube, with the function control valve 51 in the position of "raise," and with the electric motor 10 running, all the parts of the hoist and control mechanism therefor will assume the position in the illustration. When a projectile is placed on the loading platform 57 bell crank 53 will be rotated clockwise so that interlock valve 67 will be moved to the right to port fluid to the right end of the reversing valve 73 which will thereupon move to the left. Fluid acting on the left end of the tilting plate positioning piston 82 will be thus vented to the expansion tank 17 and pressure acting on the right-hand end of the piston 82 will move it to the left so that the tilting plate 13 is moved toward the stop 24. Hydraulic pump 12 will now deliver fluid to the bottom of piston

19 and start it moving upwardly. After slight upward movement, upper boss 21b on the hoist bar releases lever 91 so that bottom-of-stroke valve 72 will be moved to the right by its spring 72b. This shuts off the supply of fluid to the right end of the reversing valve 73 which is retained in its left position by its nonpositive detent 73c. As the hoist bar 20 continues its ascent the lowest hoist bar pawl 21 engages the bottom of the projectile and lifts it from the loading platform 57. When the bottom of the projectile has passed above the arm 53a of the bell crank 53 the interlock valve 67 is returned to its neutral position by the action of its spring 67b so that servo fluid can no longer flow to the bottom-of-stroke valve 72. Fluid, however, continues to be pumped through the reversing valve 73 to the right-hand end of tilting plate positioning piston 82 so that pump 12 continues to deliver fluid to the bottom of piston 19. As the hoist bar 20 approaches the top of its stroke it is uniformly decelerated by the buffer 33. At this point the projectile has passed above the lowest tube pawl 23 and it assumes its normal position beneath the bottom of the projectile. As the buffering piston 33 nears the end of its stroke, lever 91 is engaged by lower boss 21 on the hoist bar 20 to cause arm 93 to push against the top-of-stroke valve 80 to move it and the latch valve 100 to the left thus porting fluid to the left end of the reversing valve. When this member has been moved to the right, fluid acting on the right end of the tilting plate positioning piston 82 is vented to the expansion tank 17 and pressure is now exerted on the left end of the tilting plate positioning piston so that it moves toward the right stop 23 to thus reverse the flow of fluid to the hydraulic cylinder 28. Piston 19 now commences the down stroke phase of the raising cycle.

After about the first inch of downward travel of the hoist bar 20 the top-of-stroke valve 80 is released by the arm 93 so that it again assumes its rightwardly extended position and servo fluid no longer flows to the left end of the reversing valve 73. Fluid, however, continues to flow through the reversing valve to the left end of the tilting plate positioning piston 82 so that fluid is pumped to the top of the piston 19. As the hoist bar 20 descends the projectile is seated on the first tube pawl 23 above the loading platform 57. When the hoist bar approaches the bottom of its stroke, upper boss 21b thereon contacts the lever 91 causing arm 92 to shift the bottom-of-stroke valve 72 to its left position thereby admitting servo fluid to both ends of the tilting plate positioning piston 82 which is moved to the left by the pressure acting on the differential area provided by the right neutral positioning piston 83, the piston 82 being stopped in its neutral positioning when its left end abuts the extension 84b of the left neutral positioning piston 84 as hereinbefore described. As has been indicated, control fluid acts on the tube pawl control piston 103, the hoist pawl control piston 109, and the tilting plate limit piston 115 so that they are all retained in their upper position during all phases of the raising cycle.

With no projectile on the loading platform 57 all the parts of the hoist assume the position illustrated. When a second projectile is placed on the loading platform the hoist repeats the above-described cycle of operation and continues to do so as long as projectiles are supplied to the loading platform until the first pro-

jectile has reached the top and final flight in the hoist tube so that the upper interlock bell crank 61 has been rotated counterclockwise to move the interlock valve 67 to its left position. This renders the hoist inoperative even though a new projectile has been placed on the loading platform 51. However, when the upper projectile has been removed from the hoist tube the interlock valve will assume its righthand extended position so that another raising cycle may be initiated to move all projectiles one flight, and the hoist will continue to function as long as new projectiles are placed in the bottom of the hoist tube and raised projectiles are removed from the top of the hoist tube.

Assuming now that there are no projectiles in the hoist tube and the hoist tube is to be operated to lower projectiles, the operator moves the lever 52 to "lower" so that the function control valve 51 is in its down position. Servo fluid now flows through the upper passageway 70s to the interlock valve 67 but continues to flow through the passageway 70a to the various parts of the hoist control operated by servo pressure.

When a projectile is placed in the top of the hoist, upper interlock bell crank 61 is rotated counterclockwise to move interlock valve 67 to the left and admit servo fluid through the bottom-of-stroke valve to the right end of the reversing valve 73 which is moved to the left to admit fluid to the right side of the tilting plate positioning piston 82 and to vent fluid on the left side thereof to the expansion tank 17. Control fluid has already been admitted to the top of the tilting plate limit piston 115 and the tripping cam piston 109 so that they are now in their down position where they remain throughout the projectile lowering cycle. The tube pawl control valve 95 is moved to the right by control pressure acting on its differential piston 95a and tube pawl control piston 103 remains temporarily in its upper position.

As the tilting plate 13 approaches the stop 24 fluid is delivered beneath the piston 19 as before and the hoist bar starts its ascent. After approximately the first inch of ascent the bottom-of-stroke valve 72 is released and moved to its right position shutting off fluid to the right end of the reversing valve. The interlock valve 67 remains in its left position since a projectile is still seated on the uppermost position of the hoist tube biasing upper interlock bell crank 61 counterclockwise as aforesaid. As the hoist bar 20 approaches the top of its stroke the hoist bar operating lever 91 is engaged by lower boss 21b and moved counterclockwise so that rod 93a on arm 93 may move the tube pawl control valve 95 to the left to admit control fluid to the latch valve 100. At approximately this moment the projectiles are unseated from the tube pawls 23. When arm 93 has pushed the top-of-stroke valve 80 and the latch valve 100 to the left, control fluid is admitted to the upper side of the tube pawl control piston 103 to move it downwardly to retract the tube pawls 23. Control fluid is also admitted to the right end of the latch valve 100 to retain it in its left position so that control fluid will continue to flow to cylinder 104 until the bottom of the projectile is below the tube pawl from which it has been lifted.

With the top-of-stroke valve 80 in its retracted or left position servo fluid is now admitted to the left end of the reversing valve 73 which is shifted to its righthand position so that fluid is directed to the left end of the tilting plate positioning pis-

ton 82 which is moved toward the right until the left edge of the groove 82b on the top thereof abuts the depending extension 115b of the stroke limit piston 115. The tilting plate 13 is thus stopped slightly to the right of its neutral position so that only sufficient fluid is pumped to the top of the piston 19 to prevent the formation of a partial vacuum. The weight of the loaded hoist bar, however, is sufficient to move it downwardly by the force of gravity, the fluid beneath the piston 19 acting to drive the pump 12 as a motor so that the speed of descent will be held within the desired limit. When the arm 93 releases the top-of-stroke valve 80 so that it returns to its right extended position fluid will be shut off to the left end of the reversing valve 73 as aforesaid. When the bottom of the projectile is below the uppermost tube pawl 23, the rod 93a on the arm 93 moves out of contact with the tube pawl control valve 95 which is returned to its right extended position by fluid acting on its left end 95a as before described thereby shutting off control fluid supplied to the right end of the latch valve 100 and the fluid supplied to the conduit 105 leading to the top of the tube pawl control piston 103. The latch valve 100 is moved to the right by its spring 100a venting conduit 105 to the expansion tank 17 and control fluid is once again admitted to the conduit 106 so that the tube pawl control piston 103 may be forced upwardly to return the tube pawls 23 to a projectile retaining position so that as the bar 20 continues to descend the projectile will be lifted off its hoist pawl by the next lower tube pawl where it is retained until the next cycle of the hoist bar. As said bar nears the end of its down stroke the boss 21b engages the lever 91 so that arm 93 can shift the bottom-of-stroke valve 72 to the left whereby fluid is admitted equally to both sides of the tilting plate positioning piston 82 as before.

When another projectile is placed in the top of the hoist tube the interlock valve 67 is shifted to the left so that the cycle may be repeated as described. During the upstroke, when the uppermost hoist pawl approaches the bottom of the projectile seated on the next flight below the top, the upper tripping cam 108c retracts the bar pawl clear of the projectile until said pawl has been raised above the bottom of the projectile. When the hoist approaches the end of its upstroke the projectiles are lifted from the tube pawls which are again retracted as described and the hoist bar completes the down stroke phase of the lowering cycle as before indicated. This operation continues as long as projectiles are placed in the top of the hoist and removed from the bottom.

Provisions are made for operating the hoist manually for drill purposes and the like. A bypass valve 130 is provided in the lower left side of the control block 50 which may be opened to port all servo fluid supplied by servo pump 14 to the expansion tank so that the servo circuit is at the same pressure.

The tilting plate 13 is engaged by a suitable pin 13b with the manual control lever 13a which is moved in one direction or the other to control the pump 12. A signal light (not shown) in series with a switch (not shown) operated by the hoist bar may be provided to indicate when the bar reaches the top of the stroke. The operator reverses the tilting plate 13 when the signal light is energized.

Should it be desired to reverse the movement of the hoist bar after an emergency stop, the bypass valve 130 is opened to equalize the pres-

sure throughout the servo circuit. The tilting plate 13 may then be moved manually to the neutral position and the motor restarted so that the tilting plate may be shifted in the desired direction by further manual operation of the lever 13a.

It will be apparent to those skilled in the art that a variety of means could be employed for operating the valves of the hoist control other than the described linkage system; for example, solenoids energized in timed relationship with rack bar position could be used and this or equivalent means are contemplated as being within the purview of the invention. Therefore, the invention need not be confined to the precise structure and arrangement of parts shown, but may have various forms or modifications without departing from the scope of the appended claims.

The invention described herein may be manufactured and used by or for the Government of the United States of America for governmental purposes without the payment of any royalties thereon or therefor.

What is claimed is:

1. A device for moving objects between two locations comprising a hoist bar, a piston for reciprocating said hoist bar, and a control system for said hoist; said system comprising: a pump for reciprocating said bar piston, a pump discharge control piston movable between neutral and two hoist operating positions for determining the direction of bar piston movement, a circuit for conducting fluid to said control piston for actuating the same, an interlock valve in said circuit biased to closed position, means responsive to hoist load when conditioned for advancement for opening said interlock valve to cause said control piston to move to a first operating position thereby causing said hoist bar to move in the first direction of its reciprocatory cycle, said interlock valve returning to closed position upon movement of said hoist in the first direction of its reciprocatory cycle, a second valve in said circuit biased to closed position, means responsive to said hoist bar movement upon reaching the first limit of its first direction of movement in its reciprocatory cycle for opening said second valve to cause said control piston to move to a second operating position thereby reversing said hoist bar, said second valve returning to closed position upon movement of said hoist bar in said reverse direction, a third valve in said circuit biased to closed position, means responsive to said hoist bar movement upon reaching the lower limits of its reciprocatory cycle for opening said third valve to cause said control piston to move to neutral position thereby stopping said hoist bar at the end of its reciprocatory cycle until said load is again conditioned for advancement.

2. A device for moving objects between two locations by stepwise advancement of the objects through a plurality of stations comprising, a hydraulic hoist and a control system for said hoist; said hoist comprising: an object advancing bar, a hydraulic piston for reciprocating said bar, pawls retractedly mounted on said bar for engaging objects in said hoist, a stationary object guide cooperating with said bar, retractable pawls positioned in said guide at each station for supporting objects moved thereto by said bar; said hoist control system comprising: a hydraulic pump for reciprocating said bar piston, a pump discharge control piston movable to positions for determining the speed and direction of bar piston movement, an interlock valve for rendering said hoist inoperative until an operative load con-

dition prevails thereon, means responsive to said operative load condition for moving said interlock valve to hoist operating position, a reversing valve cooperating with said interlock valve for determining a first position of said control piston, a top-of-stroke valve responsive to said hoist bar movement upon its reaching the upper limit of its reciprocatory cycle for actuating said reversing valve in opposition to the effect of the interlock valve thereon to move said control piston to a second position thereby reversing said bar piston, and a bottom-of-stroke valve responsive to said hoist bar movement upon its reaching the lower limit of its reciprocatory cycle for moving said pump control piston to a third position stopping the pump discharge to the bar piston, thereby stopping said hoist at the end of its reciprocatory cycle.

3. A device for moving objects between two locations by stepwise advancement of the objects through a plurality of stations comprising; a hydraulic hoist and a control system for said hoist; said hoist comprising: an object advancing bar, a hydraulic piston on said bar for reciprocation thereof, pawls retractedly mounted on said bar for engaging objects in said hoist to advance them one station for each reciprocation of said bar, and a stationary object guide cooperating with said bar; said hoist control comprising: a hydraulic pump for reciprocating said bar piston, a pump discharge control piston movable between a neutral and two hoist operating positions for determining the direction of bar piston movement, an interlock valve for rendering said hoist inoperative until an operative load prevails thereon, means responsive to said operative load in said hoist for actuating said interlock valve for starting said hoist, a reversing valve cooperating with said interlock valve for moving said control piston to its first hoist operating position, means responsive to said hoist bar movement upon its reaching the first limit of its reciprocatory cycle for actuating said reversing valve in opposition to the effect of the interlock valve thereon thereby moving said control piston to its second hoist operating position, and means responsive to said hoist bar movement upon reaching the end of its reciprocatory cycle for placing said pump control piston in neutral position thereby stopping said bar piston until an operative load condition again prevails in said hoist.

4. A device for moving objects between two locations by stepwise advancement of the objects through a plurality of stations comprising; a hydraulic hoist and control system for said hoist; said hoist comprising: an object advancing bar, a hydraulic piston for reciprocating said bar, pawls retractedly mounted on said bar for engaging objects in said hoist, a stationary object guide cooperating with said bar, retractable pawls positioned in said guide at each station for supporting objects moved thereto by said bar; said hoist control comprising: a hydraulic pump for reciprocating said bar piston, a pump discharge control piston for determining the direction of bar piston movement, an interlock valve responsive to the load condition in said hoist for initiating hoist operations, a reversing valve cooperating with said interlock valve for determining the position of said control piston, a top-of-stroke valve responsive to said hoist bar movement upon its reaching the upper limit of its reciprocatory cycle for actuating said reversing valve in opposition to the effect of the interlock valve thereon thereby reversing said bar piston, a bottom-of-

stroke valve responsive to said hoist bar movement upon its reaching the lower limit of its reciprocatory cycle for placing said pump control piston in neutral position, a directional control valve movable between object raising and object lowering position for establishing the direction of object movement, and means cooperating with said last named valve in object lowering position to retract said bar pawls and said guide pawls in correlation with hoist bar position to accomplish the lowering of objects in said hoist.

5. A device for moving objects between two locations by stepwise advancement of the objects through a plurality of stations comprising; a hydraulic hoist and control system for said hoist; said hoist comprising: an object advancing bar having a reciprocating cycle of operation, pawls retractedly mounted on said bar for engaging objects in said hoist, a stationary object guide cooperating with said bar, retractable pawls positioned in said guide at each station for supporting objects moved thereto by the reciprocation of said bar; said hoist control comprising: means for reciprocating said bar, a hydraulic control piston for actuating said reciprocating means, the movement of said bar being dependent upon the position of said piston, an interlock valve for rendering said hoist inoperative until an operative load condition prevails in said hoist, means responsive to said operative load condition for moving said interlock valve to hoist operation position, a reversing valve cooperating with said interlock valve for determining a first position of said control piston to move said bar upwardly, a top-of-stroke valve responsive to said hoist bar movement upon its reaching the upper limit of its reciprocatory cycle for actuating said reversing valve in opposition to the effect of the interlock valve thereon thereby reversing said bar, and a bottom-of-stroke valve responsive to said hoist bar movement upon its reaching the lower limit of its reciprocatory cycle for placing said control piston in a nonbar operating position thereby stopping said hoist until an operative load condition again prevails in said hoist.

6. In a conveyor for moving objects between two locations by stepwise advancement of the objects through a plurality of stations, a control system therefor comprising: means for reciprocating said conveyor substantially over the span between stations, a hydraulic pump for operating said conveyor reciprocating means, a pump control means movable between a conveyor stop and two conveyor operating positions, an interlock valve for rendering said conveyor operative only under a predetermined load condition thereon, means responsive to conveyor load condition for controlling said interlock valve, a reversing valve cooperating with said interlock valve for moving said control means to one of said two conveyor operating positions, means responsive to conveyor movement upon its advancing objects substantially the distance between two stations for actuating said reversing valve in opposition to the effect of the interlock valve thereon for moving said control means to the second of said two conveyor operating positions to reverse said conveyor, means for supporting said objects at each station when advanced thereto by said conveyor, means responsive to said conveyor movement in its reverse direction for moving said pump control means to conveyor stop position, and a function control means for establishing the direction of object movement by said conveyor.

7. A device for moving objects from a first to a

second station comprising a hoist bar, a piston for reciprocating said hoist bar, means for retaining said objects at said stations, and a control system for said hoist; said control system comprising:

- 5 a pump for reciprocating said bar piston, a pump discharge control piston movable between hoist operating and hoist stop positions, a circuit for conducting fluid to said second piston for actuating the same, load operated means at said stations of said hoist for retaining said circuit closed with an object in said second station, said means being responsive to the placing of an object in the first station and the removal of an object from the second station for opening said circuit to cause said second piston to move to a hoist operating position, a top-of-stroke valve in said circuit biased to closed position, means responsive to said hoist bar movement upon reaching the upper limit of its reciprocatory cycle for opening said top-of-stroke valve to move said second piston to a position reversing said hoist bar movement, a bottom-of-stroke valve in said circuit biased to closed position, and means responsive to said hoist bar movement upon reaching the lower limit of its reciprocatory cycle for opening said bottom-of-stroke valve to cause said second piston to move to hoist stop position, and a function control valve for determining the direction of object movement.
- 30 8. A device for raising and lowering objects by stepwise advancement of the objects through a plurality of successive stations comprising a hydraulic hoist and a control means therefor; said hoist comprising an object advancing bar, pawls mounted thereon for engaging and advancing said objects, a hydraulic piston for linearly reciprocating said bar, a stationary object guide cooperating with said bar, pawls positioned on said guide at each station for supporting objects advanced thereto during bar reciprocation, means for positively retracting said bar pawls, means for positively retracting said guide pawls, the direction of object movement during operation of the hoist being determined by the operation of said guide and bar pawl retracting means; said bar pawl retracting means comprising: a piston operable between bar pawl tripping and nontripping position and biased to nontripping position; said guide pawl retracting means comprising: a piston operable between guide pawl extended and guide pawl retracted positions and biased to pawl retracted position; a circuit for conducting fluid to said last two mentioned pistons, a function control valve in said circuit movable between object lowering and object raising positions, said valve in object lowering position admitting fluid through a branch of said circuit to said bar pawl piston to replace it in pawl tripping position, a guide pawl control valve in the second branch of said circuit biased to closed position, means responsive to upward hoist bar movement for opening said guide pawl control valve, a latch valve in said second circuit biased to closed position, means responsive to hoist bar movement upon its reaching substantially the upper limit of its reciprocatory cycle for opening said latch valve thereby moving said guide pawl piston to pawl retracted position, means for locking said latch valve in open position until closure of said guide pawl control valve, said latch and said guide pawl control valve returning to closed position upon said hoist bar lowering said object below the guide pawls theretofore supporting said objects and below the guide pawls control valve actuating position of said hoist bar, said guide pawls

21

being extended upon closing of said valves to receive objects being lowered; said control means for said hoist comprising a pump for reciprocating said bar piston, and a pump discharge control means for determining the direction of bar piston movement; thereby providing for the raising or lowering of objects by reciprocation of said bar and the cooperation of the pawls therewith.

9. A device for moving objects between two locations by stepwise advancement of the objects through a plurality of stations comprising, a hydraulic hoist and a control system for said hoist; said hoist comprising: an object advancing bar, a reciprocable hydraulic piston on said bar, pawls retractedly mounted on said bar for engaging objects in said hoist, a stationary object guide cooperating with said bar, retractable pawls positioned in said guide at each station for supporting objects moved thereto by said bar; said hoist control system comprising, a hydraulic pump for reciprocating said hydraulic bar piston, a pump
